FIG. 1

FIG. 2

FIG. 3

FIG. 4

FIG. 5

FIG. 1 is a side elevational view of a container for projectiles showing our new design;

FIG. 2 is a vertical sectional view thereof taken on the line 2—2 of FIG. 1.

FIG. 3 is a bottom plan view thereof;

FIG. 4 is a top plan view thereof; and

FIG. 5 is a fragmentary elevational view on an enlarged scale, illustrating the mating extremities of the top and bottom portions of the container in disassembled relationship.

The side of the container opposite to that illustrated in FIG. 1 of the drawings is a mirror image thereof.

We claim:

The ornamental design for a container for projectiles, as shown and described.
